CLAIM

The ornamental design for ventilation fan grille, as shown and described.

DESCRIPTION

FIG. 1 is a bottom perspective view of ventilation fan grille showing our new design;

FIG. 2 is a front view thereof;

FIG. 3 is a rear front view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof; and,

FIG. 9 is a view identical to FIG. 1, but shown with the broken line environmental subject matter in a position of use.

The broken lines shown in FIG. 9 illustrate environmental structure, and the broken lines in the remaining views illustrate portions of the ventilation fan grille. None of the broken lines form part of the claimed design.
